United States Patent Office

Des. 177,771
Patented May 22, 1956

177,771

FOUNDATION GARMENT

Alice Christina Sparadoski, Valhalla, N. Y.

Application December 1, 1955, Serial No. 39,128

Term of patent 14 years

(Cl. D3—17)

FIG. 1.

FIG. 2.

Figure 1 is a front elevational view of the foundation garment, embodying my new design, and Fig. 2 is a rear elevational view thereof.

I claim:

The ornamental design for a foundation garment, substantially as shown.
